(57) **CLAIM**

The ornamental design for spectacles as shown and described.

DESCRIPTION

FIG. 1 is a top front perspective view of the spectacles of my design;

FIG. 2 is a front elevational view thereof;

FIG. 3 is a rear elevational view thereof;

FIG. 4 is a right-side view thereof;

FIG. 5 is a left side view thereof;

FIG. 6 is a bottom view thereof;

FIG. 7 is a top view thereof;

FIG. 8 is a top front perspective detail of an arm of the spectacles of FIG. 1;

FIG. 9 is a top rear perspective detail of an arm of the spectacles of FIG. 1 in an open configuration; and,

FIG. 10 is a top front perspective detail of an arm of the spectacles of FIG. 1 in an open configuration.

The evenly dashed broken lines in the figures show portions of the spectacles and form no part of the claimed design. The unevenly dashed broken lines in FIGS. 8-10 demarcate the boundaries of the detail views and form no part of the claimed design.
